US0D1080286S

(12) **United States Design Patent** (10) Patent No.: **US D1,080,286 S**
(45) Date of Patent: ** Jun. 24, 2025

(54) **ESPRESSO COFFEE MACHINE**

(71) Applicant: **SMEG S.P.A.**, Guastalla (IT)

(72) Inventor: **Bujar Taga**, Guastalla (IT)

(73) Assignee: **SMEG S.P.A.** (IT)

(**) Term: **15 Years**

(21) Appl. No.: **35/521,846**

(22) Filed: **Jul. 31, 2023**

(80) **Hague Agreement Data**

Int. Filing Date: **Jul. 31, 2023**

Int. Reg. No.: **DM/231333**

Int. Reg. Date: **Jul. 31, 2023**

Int. Reg. Pub. Date: **Aug. 2, 2024**

(57) **CLAIM**

The ornamental design for an espresso coffee machine as shown and described.

DESCRIPTION

1. Espresso coffee machine

1.1 : Perspective

1.2 : Front

1.3 : Back

1.4 : Left

1.5 : Right

1.6 : Top

1.7 : Bottom

Use: the design is incorporated into a coffee machine, in particular an espresso coffee machine; innovative part: the innovative points of the design are in the shape of the coffee machine, as shown in the drawings; figure that best illustrates the design: perspective view (figure 1.1); the dotted lines show the parts of the espresso coffee machine that are excluded from protection, as they are not part of the claimed design.

1 Claim, 7 Drawing Sheets
